KNOT-TYING MECHANISM

Edward Hall Parker, Somerville, Mass., assignor
to Edward A. Taft, trustee, Boston, Mass.

Application June 6, 1931, Serial No. 542,583

32 Claims. (Cl. 289—3)

This invention has particular reference to mechanism for tying weaver's knots. Among the salient objects of the invention are the provision of relatively simple means for positioning the threads in the mechanism, means for holding the strands under proper control at all times so that the convolutions of the knot shall be correctly formed, the attainment of simplicity and compactness in the mechanism, and protection of the mechanism against damage in ordinary handling under actual mill conditions.

In the accompanying drawings:

Figure 1 is a perspective view showing the invention embodied in a hand knoter, the mechanism being in the initial position, and the manner of holding the implement and introducing the threads thereinto being indicated in dotted lines.

Fig. 2 is a top plan view of the mechanism with the upper portion of the housing and certain other parts omitted.

Figs. 3, 4 and 5 are vertical sectional views taken along the lines 3—3, 4—4 and 5—5, respectively, of Fig. 2. In Figs. 3 and 4 the parts are shown in the initial position. In Fig. 5 the mechanism is shown in the position occupied when the thumb lever is fully depressed.

Fig. 6 is a horizontal section taken along the line 6—6 of Fig. 4.

Fig. 6^a is a detail side view of the friction thread-holding plate 51.

Figs. 7 and 8 are fragmental views illustrating the construction and operation of the yarn-clamping member 13. Fig. 7 shows the clamping member 13 in initial position, while Fig. 8 shows said member in effective position.

Figs. 9 and 10 are fragmentary views showing the construction and operation of the shear which cuts off those portions of the yarn which are destined to become waste, the shear being shown closed in Fig. 9 and open in Fig. 10.

Figs. 11 and 12 are fragmentary views illustrating the construction and operation of the finger which strips the knot off the posts 11 and 12 and tightens the knot, said finger being shown in its operative position in Fig. 11 and in its initial position in Fig. 12.

Fig. 12^a is a detail view of the lever 87 and the pawl 90.

Fig. 13 is a vertical sectional view in the plane of line 13—13 of Fig. 4 to illustrate the driving means for the helical finger 52.

Fig. 14 is a fragmentary perspective view illustrating the position occupied by the two yarns just prior to the knotting operation.

Figs. 15, 16, 17, 18, 19 and 20 are perspective views showing successive stages in the operation of tying the knot.

The embodiment which has been selected to illustrate the invention comprises a supporting

framework that includes a casing 1, a downwardly extending handle portion 2 to which a strap 3 is attached, and a bracket 4 projecting forwardly from the casing 1.

The means for supporting the two yarns which are to be tied together and for causing them to extend across each other may be of various forms, that herein shown comprising two parallel upwardly extending plates 5 and 6 secured to the bracket 4. In these plates are cut yarn-receiving and guiding slots 7 and 8, and 9 and 10, respectively. It will be noted that the two rearward slots 7 and 9 are inclined downwardly and forwardly toward the forward slots 8 and 10, respectively. The slot 7 extends to a point below and slightly forward of the lower end of the slot 8. The slot 10 extends below and slightly to the rear of the lower end of the slot 9. Preparatory to the tying of a knot the two yarns are placed in the guide slots with their short ends to the right of the plate 6. The yarn A is inserted in the two rear slots 7 and 9. Simultaneously, the other yarn B is placed in the slots 8 and 10. Due to the relative positions of the lower ends of these several slots, when the two yarns are thus positioned they cross each other at a point approximately behind a stationary vertical tying post 11 located midway between the guide plates 5 and 6. In this initial position, that portion of the yarn B which extends between the post 11 and the slot 10 lies behind a stationary vertical detent post 12. This post is of such height as not to interfere with subsequent forward movement of the yarn A.

Means is provided for clamping the strand B in the lower end of the slot 8. The means herein shown for this purpose comprises a lever or finger 13 (Fig. 7) located between the plate 5 and a friction guide plate 14 attached to the outer side of the plate 5. The strand B lies within a slot 15 in the plate 14. The finger 13 is pivoted on a stud 16 and its upper end is arranged to swing across the slots 8 and 15, as shown in Fig. 8, and thus clamp the yarn B. On the lower end of the lever 13 is a stud 17 that lies between two lugs 18 (Fig. 6) on a slide 19 (Fig. 6). The slide is reciprocable in a guideway formed between the bracket 4 and a block 20 fixed to said bracket.

Referring now to Fig. 3: The rear end of the slide 19 is connected through the medium of a spring 21 to a trip member 22 which is mounted on a pivot 23 that is carried by the casing 1. The spring 21 normally holds a lug 24 on the slide 19 against a lug 25 on the trip member 22. The end of the lug 25 normally lies between the lug 24 and a short projection 26 on the slide.

In the present embodiment of the invention, the means employed to oscillate the trip member 22 comprises a thumb lever 27 mounted on the pivot 23 and detachably connected to the trip

member by means of a pawl 28, said pawl being pivoted to the thumb lever 27 at 29 and being arranged to engage a projection 30 on the trip member. A compression spring 31 normally holds the pawl in engagement with the projection 30. A torsion spring 32 (Fig. 4) coiled about the pivot 23 bears at one end against a pin 33 on the frame, and at its other end against a pin 34 on the thumb lever 27, said spring normally holding the thumb lever in the position shown in Figs. 1 to 4. A similar torsion spring 35 (Fig. 9) coiled around the pivot 23 bears at one end against a pin 36 on the frame and at its other end against a pin 37 on the trip member 22. The spring 35 normally holds the trip member in the position shown in Fig. 3. Contact of the portion 38 of the trip member with the portion 39 of the frame limits the action of the spring 35. It will be seen that when the thumb lever 27 is depressed by the operator, the pawl 28 will cause the trip member 22 to move with the thumb lever until engagement of the lower end 40 (Fig. 3) of the pawl with the cam surface 41 causes the pawl to swing away from the projection 30, whereupon the torsion spring 35 restores the trip member 22 to its normal position.

The downward stroke of the thumb lever and the accompanying movement of the trip member produces a forward movement of the slide 19 (Fig. 3), thus causing the lever 13 to clamp the yarn B. Pressure of the lug 25 against the lug 26 causes forward movement of the slide 19 if there be excessive starting resistance due to friction and to tension of the yarn. However, after positively moving the slide a short distance, the lug 25 swings away from the lug 26, continued forward movement of the slide being dependent on the spring 21. In the return movement of the trip member 22, the lug 25, bearing against the lug 24, restores the slide 19 to its normal position, and moves the clamping lever 13 to its withdrawn position as shown in Fig. 7.

Upon comparing Figs. 14 and 15, it will be seen that in Fig. 15 the yarn A has been looped over the yarn B, and that that portion of the yarn B which extends between the stationary post 12 and the slot 10 has been drawn forward, the extra yarn needed for the loops having been drawn from the slots 7, 9 and 10. The means employed for this purpose comprises two pins 42 and 43. In their initial positions, the pins 42 and 43 are behind the yarns, as shown in Fig. 14. The pin 42 is short enough to pass under the yarn B, whereas the pin 43 is tall enough to engage both of the yarns. The pins have yarn-receiving notches, as shown in Fig. 17. These pins are fixed to levers 44 and 45, respectively (Fig. 6), which are pivoted on fixed studs 46 that extend downwardly from the block 20. The pins 42 and 43 extend up through clearance slots 47 in the block 20. A stud 48 (Fig. 6) fixed to the slide 19 extends into arcuate slots 49 in the levers 44 and 45. Accordingly, as the thumb lever 27 is depressed and the slide 19 advanced, the levers 44 and 45 swing toward each other thus causing the pins 42 and 43 to advance and approach each other, whereby the yarns A and B are drawn into the positions shown in Fig. 16 and clamped against a stationary abutment 50 (Figs. 3 and 14). The slide 19, being yieldingly connected to the trip member 22, stops when the yarns are clamped against the abutment. Undue looseness of the yarns between the abutment 50 and the slots 7, 9 and 10 is prevented by means of the friction plate 14 and a similar plate 51 (Figs. 1, 2 and 6a). These

plates each have two slots which do not quite register with the lower ends of the slots 7, 8, 9 and 10, respectively, and thus cause bends in the yarns, the resulting friction being sufficient to prevent undue looseness of the strands.

As shown in Fig. 15, the advance of the pins 42 and 43 resulted in the formation of a loop or bight A' in the yarn A. In order to loop the yarn B around said bight, as shown in Fig. 17, and draw said yarn B down through the space 10 between said bight and the post 12, I provide a helical finger 52 having a hook 53 at its forward end. The rear end of the finger 52 is fixed to a tubular screw 54 which is rotatable and axially movable in a bore 55 in the housing 1. A stud 56 projects into said bore and into the helical groove of the screw 54 and thus causes the screw to move axially as it rotates. Rotation is imparted to the screw 54 by means which, in the present instance, comprises a shaft 57, the rear end of which is 15 journaled in the housing 1 at 58, said shaft lying within the tubular screw 54. The rear portion of the screw 54 is longitudinally slotted to receive the ends of a pin 59 that extends through the shaft 57, said pin and slots forming virtually a 20 splined connection between the screw and the shaft. The latter is driven by means of a gear train consisting of a pinion 60 and three segmental gears 61, 62 and 63 (Fig. 13), the segment pinion 62 being integral with the segment gear 30 61. The gears 61 and 62 are mounted on a frame stud 64. The gear 61 is supported on a frame stud 65. In order to prevent the pinion 60 from turning too far in either direction, the segment 35 63 is provided with stop surfaces 66 and 67 to engage with the ends of the segment 61. On the segment 63 is a roller 68 that lies within a cam groove 69 formed in the rear portion of the trip member 22. It will be seen that as the trip member oscillates the helical finger 52 will be advanced and retracted. The size and lead of the finger 52 are such that as it advances the hook 53 passes under the yarn B at a point between the posts 11 and 12, and then encircles the bight A', making in all two revolutions. Just before 40 the finger 52 reaches its extreme forward position, its forward end pushes the yarn B slightly to the right at a point close to the clamping post 45 43 (see Fig. 16), thus enabling the hook 53 to pass to a point above the yarn B.

In order that there shall be a free end of the yarn B which may be taken by the hook 53 when the finger 52 is withdrawn, and also for the purpose of trimming off the waste end of the yarn A, I provide a shear located just at the right of the clamping member 50. In this embodiment of the invention, the shear comprises a stationary blade 70 (Fig. 10) and a movable blade 71. The stationary blade is secured to a bracket 72 attached to the block 20. In the shank portion of the blade 60 71 is a slot 73 through which extends a pivot stud 74, said stud penetrating the blade 70 and engaging the bracket 72. A compression spring 75 (Fig. 2) interposed between the head of the pivot stud and the blade 71 serves to maintain the shear 65 blades in close contact.

To sever the yarns A and B, downward and forward movement is imparted to the blade 71 by means herein shown as comprising a lever 76 pivoted between its ends to the block 20 at 77 and pivoted at its upper end to the blade 71 at 78. The lower end of the lever 76 is pivoted at 79 to a one-piece pawl 80 that extends rearwardly into position to overlie and be engaged by a finger 75

81 in the rearward movement of the latter, said finger being rigid with the trip member 22. A compression spring 82 holds the pawl 80 in contact with said finger. When the finger 81 moves forward (i. e., clockwise), its rear end slips under and in front of the tooth of the pawl 80, and when the finger moves rearwardly it draws the pawl with it until the engagement of the cam surface 83 on the pawl with the upper edge of the finger causes disengagement of the pawl and finger, whereupon a contractile spring 84 (Fig. 5) restores the blade 71 to its normal position. Fig. 9 shows the pawl as about to be disengaged from the finger 81. The yarns A and B having been severed by the shear 70-71 (as indicated in Fig. 17), the helical finger 52 is retracted, carrying with it the yarn B as shown in Figs. 17, 18 and 19, the severed end of the yarn B slipping out from between the clamping members 43 and 50.

20 The knot is drawn tight and stripped from the posts 11 and 12, and the yarns pulled away from the clamping posts 42 and 43 and the helical finger 52, by means which, in this embodiment of the invention, comprises a finger 85 (Figs. 11, 25 12 and 19) which underlies that portion of the 20 yarn B that extends between the slot 8 and the post 11. Said finger is pivoted at 86 on the cover 25 block 11. A lever 87 is connected to the finger 85 by means of a pivot 88 lying in a slightly elongated opening. The lever 87 is pivoted to the 30 frame at 89. A pawl 90 is pivoted at 91 to the lower portion of the lever 87. On this pawl is a lug 92 which is pressed rearwardly by a compression spring 93 that bears against a lug 92* on the 35 pawl. The lug 92 normally rests against a lug 94 (Fig. 13) on the gear segment 61. The normal position of the finger 85 is shown in Figs. 12 and 14. When the thumb lever 27 is depressed, the gear segment 61 swings to the right as viewed in Fig. 13 (thereby carrying the lug 94 up and away from the lug 92), the spring 93 swings the pawl 90 rearwardly to place the lug 92 in the path of the return movement of the lug 94, so that in such return movement the lower end of the lug 94 strikes the lug 92 and swings the lever 87 into the position shown in Fig. 11, thereby raising the lever 85 into the position shown in Figs. 11, 19 and 20. As the thumb lever returns to its normal position, a pin 95 on said lever engages a lug 96 on the lever 87 and restores the lever 85 to its initial position.

Preparatory to the tying of a knot, the operator takes the two yarns and draws them across the plates 5 and 6, whereby the yarns are placed in position in the guide slots with their short ends to the right of the guide plate 6, as shown in Fig. 1. In the operation of placing the yarns in said guide slots, the yarns become disposed as shown in Fig. 14. The thumb lever 27 is then depressed, as a result of which the clamping finger 13 is actuated to clamp the yarn B in the slots 8 and 15, and the pins 42 and 43 move forward, the pin 42 carrying a portion of the yarn A into clamping engagement with the clamping member 50, and the pin 43 carrying portions of the yarns A and B into clamping engagement with said member 50, whereby a bight A' is formed in the yarn A, as shown in Fig. 15. Soon after the pins 42 and 43 start moving forward, the helical finger 52 also begins to advance, as indicated in Fig. 15, said finger continuing to advance after the pins 42 and 43 have stopped against the clamping member 50. The hook 53 of the helical finger 52 follows a helical path around the bight A', as indicated in Fig. 16. As the hook is ap-

proaching the end of its forward movement it presses aside the portion of the yarn B which extends between the post 12 and the clamping pin 43 sufficiently to permit the hook 53 to pass above the yarn, whereupon the yarn springs back under the hook. Just before the helical finger 52 is retracted, the shear 70, 71 is actuated, as indicated in Fig. 9, to sever both yarns close to the clamping pin 43, as indicated in Fig. 17. An instant after the yarns are thus severed the helical finger 52 is retracted through the action of the spring 35, thereby drawing the free end of the yarn B around the bight A', as shown in Fig. 17, and through the space between said bight and the loop of yarn B that extends around the post 12 (see Fig. 18), thus completing the convolutions of the knot. As the finger 52 completes its return movement, the finger 85 flies up, lifting the yarn B (which is clamped in the slot 8), thereby stripping the convolutions of the knot off the posts 11 and 12 and drawing the convolutions tight, as shown in Fig. 20. A moment after the finger 85 has performed its function, the clamping members 13, 42 and 43 return to their initial positions, thereby releasing the yarns and permitting the operator to withdraw them from the knitter. When the operator allows the thumb lever 27 to return to its upper position, the finger 85 is lowered to its normal position as illustrated in Fig. 4.

It will be seen that the introduction of the yarns into the knitter is a very simple operation. The yarns are held under proper control at all times during the tying of the knot, and hence the convolutions of the knot are always formed in proper relation to one another, thereby insuring the correct formation of the knot.

The mechanism is quite compact in comparison with various weaver's knotters of the prior art, and is well protected against damage due to the rough handling which a knitter is apt to receive under mill conditions.

In the foregoing description and in the claims, the term "yarn" has been used in a generic sense to include all analogous materials.

It will be understood that the invention is susceptible of embodiment in various forms of automatic power-driven machinery as, for example, winders of the types disclosed in the Colman Patents Nos. 1,267,977 and 1,611,890.

I claim as my invention:

1. A weaver's knitter comprising means to support two yarns A and B in crossed relation; a clamp to hold the yarn B; a post near the crossing point; a second post near the first post; two pins for drawing the yarn A into the form of a bight enclosing the yarn B and for clamping the end portions of said bight, one of said pins serving to bend the yarn B around the second post and clamp it adjacent to the end portions of said bight; a shear for severing both yarns adjacent to the last-mentioned pin; a helical finger having a hook at its tip; means for advancing and retracting said finger in a helical path which encloses said bight, said hook being arranged to engage the yarn B adjacent to the last mentioned pin when the finger reaches its advanced position and to draw the yarn B around said bight and into the space between said bight and the second post in the retracting movement of said finger; and a pivoted lever arranged to engage the yarn B at a point between said clamp and the first post to strip the knot from said posts and tighten the knot.

2. A weaver's knotter comprising means to support two yarns A and B in crossed relation; a clamp to hold the yarn B; a post near the crossing point; a second post near the first post; two pins for drawing the yarn A into the form of a bight enclosing the yarn B and for clamping the end portions of said bight, one of said pins serving to bend the yarn B around the second post and clamp it adjacent to the end portions of said bight; means for cutting off the waste ends of both yarns adjacent to the last-mentioned pin, means to engage the yarn B adjacent to the last-mentioned pin and draw it around said bight and into the space between said bight and the second post; and means arranged to engage the yarn B at a point between said clamp and the first post to strip the knot from said posts and tighten the knot. 5
3. A weaver's knotter comprising means to support two yarns A and B in crossed relation; a clamp to hold the yarn B; a post near the crossing point; a second post near the first post; means for drawing the yarn A into the form of a bight enclosing the yarn B, for clamping the end portions of said bight, for bending the yarn B around the second post, and for clamping the yarn B adjacent to the end portions of said bight; means for cutting off the waste ends of both yarns; a helical finger having a hook at its tip, means 10 for advancing and retracting said finger in a helical path which encloses said bight, said hook being arranged to engage the yarn B when the finger reaches its advanced position and to draw the yarn B around said bight and into the space between said bight and the second post in the retracting movement of said finger, and means arranged to engage the yarn B at a point between said clamp and the first post to strip the knot from said posts and tighten the knot. 15
4. A weaver's knotter comprising means to support two yarns A and B in crossed relation; a clamp to hold the yarn B; a post near the crossing point; a second post near the first post; means for drawing the yarn A into the form of a bight enclosing the yarn B, for clamping the end portions of said bight, for bending the yarn B around the second post and for clamping the yarn B adjacent to the end portions of said bight; means for cutting off the waste ends of both yarns to provide shortened ends; a hook; means for advancing and retracting said hook in a helical path which encloses said bight, said hook being arranged to engage the shortened end of the yarn B upon reaching its advanced position and draw said shortened end around said bight and into the space between said bight and the second post in the retracting movement of said hook, and means to strip the knot from said posts and tighten the knot. 20
5. A weaver's knotter comprising means to support each of two yarns A and B at two separated points; a post located about midway between said points; a second post near the first post; means for drawing the yarn A into the form of a bight enclosing the yarn B, for clamping the end portions of said bight, for bending the yarn B around the second post and for clamping the yarn B adjacent to the end portions of said bight; means for cutting off the waste ends of both yarns to provide shortened ends, means to draw the shortened end of the yarn B around said bight and into the space between said bight and the second post; and means to strip the knot from said posts and tighten the knot. 25
6. A weaver's knotter comprising means to support each of two yarns A and B at two separated points; a post located about midway between said points; a second post near the first post, said posts being in front of said yarns; two devices, one at each side of said posts, for drawing the yarn A forward into the form of a bight enclosing the yarn B, for clamping the end portions of said bight, for bending the yarn B around the second post and for clamping the yarn B adjacent to the end portions of said bight; a stationary abutment against which said devices clamp the yarns; means for cutting off the waste ends of both yarns adjacent to said abutment to provide shortened ends; a hook to draw the shortened end of the yarn B around said bight and into the space between said bight and the second post; and means to strip the knot from said posts and tighten the knot. 30
7. A weaver's knotter comprising means to support each of two yarns A and B at two separated points; a post located about midway between said points; a second post near the first post; means for drawing the yarn A into the form of a bight enclosing the yarn B, for clamping the end portions of said bight, for bending the yarn B around the second post and for clamping the yarn B adjacent to the end portions of said bight; means for cutting off the waste ends of both yarns to provide shortened ends; a hook; means for advancing and retracting said hook in a helical path which encloses said bight, said hook being arranged to engage the shortened end of the yarn B upon reaching its advanced position and draw said shortened end around said bight and into the space between said bight and the second post in the retracting movement of said hook, and means to strip the knot from said posts and tighten the knot. 35
8. A weaver's knotter comprising means to support each of two yarns A and B at two separated points; a post located about midway between said points; a second post near the first post; means for drawing the yarn A into the form of a bight enclosing the yarn B, for clamping the end portions of said bight, for bending the yarn B around the second post and for clamping the yarn B adjacent to the end portions of said bight; means for cutting off the waste ends of both yarns to provide shortened ends, means to draw the shortened end of the yarn B around said bight and into the space between said bight and the second post; and means to strip the knot from said posts and tighten the knot. 40
9. A weaver's knotter comprising means to support each of two yarns A and B at two separated points; a post located about midway between said points; a second post near the first post, said posts being in front of said yarns; two devices, one at each side of said posts, for drawing the yarn A forward into the form of a bight enclosing the yarn B, for clamping the end portions of said bight, for bending the yarn B around the second post and for clamping the yarn B adjacent to the end portions of said bight; a stationary abutment against which said devices clamp the yarns; means for cutting off the waste ends of both yarns adjacent to said abutment to provide shortened ends; a hook to draw the shortened end of the yarn B around said bight and into the space between said bight and the second post; and means to strip the knot from said posts and tighten the knot. 45
10. A weaver's knotter comprising means to support two yarns A and B in crossed relation; a post near the crossing point; a second shorter post near the first post, said posts being in front of the yarns; two pins, one at each side of said posts, for drawing the yarn A forward into the form of a bight enclosing the yarn B, for clamping the end portions of said bight, for bending the yarn B around the second post and for clamping the yarn B adjacent to the end portions of said bight; means for cutting off the waste ends of both yarns to provide shortened ends; a hook to draw the shortened end of the yarn B around said bight and into the space between said bight and the second post; and means to strip the knot from said posts and tighten the knot. 50

form of a bight enclosing the yarn B and for clamping the end portions of said bight, one of said pins being taller than the other and thus adapted to engage the yarn B and bend it around 5 the second post and clamp it adjacent to the end portions of said bight; a stationary abutment against which said pins clamp the yarns; means for cutting off the waste ends of both yarns adjacent to said abutment to provide shortened 10 ends; means to draw the shortened end of the yarn B around said bight and into the space between said bight and the second post; and means to strip the knot from said posts and tighten the knot.

15 11. A weaver's knotter comprising means to support two yarns A and B in crossed relation; a post in front of and near the crossing point; two members, one at each side of said post, for drawing the yarn A forward into the form of a bight enclosing the yarn B, one of said members being adapted to engage the yarn B and position it adjacent to the end portions of said bight, means for cutting off the waste ends of both 20 yarns to provide shortened ends, means to draw the shortened end of the yarn B around said bight; and means to strip the knot from said post and tighten the knot.

12. A weaver's knotter comprising means to support two yarns A and B in crossed relation; 30 a post in front of and near the crossing point; two members, one at each side of said post, for drawing the yarn A forward into the form of a bight enclosing the yarn B and for clamping the end portions of said bight, one of said members being adapted to engage the yarn B and position it adjacent to the end portions of said bight; an abutment against which said members clamp the yarns; means for cutting off the waste ends of both yarns adjacent to said abutment to provide 35 shortened ends; means to draw the shortened end of the yarn B around said bight; and means to strip the knot from said post and tighten the knot.

13. A weaver's knotter comprising means to support two yarns A and B in crossed relation; 45 a post near the crossing point; a second shorter post near the first post, said posts being in front of the yarns; two members, one at each side of said posts, for drawing the yarn A forward into the form of a bight enclosing the yarn B and for clamping the end portions of said bight, one of said members being adapted to engage the yarn B and bend it around the second post and clamp it adjacent to the end portions of said bight; an 50 abutment against which said members clamp the yarns; means for cutting off the waste ends of both yarns adjacent to said abutment to provide shortened ends; means to draw the shortened end of the yarn B around said bight and into the space between said bight and the second post; and means to strip the knot from said posts and tighten the knot.

14. A weaver's knotter comprising means to support two yarns A and B in crossed relation; a 65 post near the crossing point; a second post near the first post, said posts being in front of the yarns; two pins, one at each side of said posts, for drawing the yarn A forward into the form of a bight enclosing the yarn B, one of said pins being adapted to engage the yarn B and bend it around the second post; means to draw the 70 yarn B around said bight and into the space between said bight and the second post; and means to strip the knot from said posts and tighten the knot.

15. A weaver's knotter comprising means to support a yarn A and a yarn B, the former being in the form of a bight enclosing the latter; a helical finger having a hook at its tip; means for advancing and retracting said finger in a helical path which encloses said bight, said hook being arranged to engage the yarn B when the finger reaches its advanced position and to draw the yarn B around said bight and into a space between said bight and the yarn B in the 5 retracting movement of said finger; and means for tightening the knot.

16. In a weaver's knotter, devices for supporting a yarn A and a yarn B, the former being in the form of a bight enclosing the latter, said 15 devices including a post across which the yarn B extends and which holds the closed end of the bight, a helical finger having a hook at its tip, means for advancing and retracting said finger in a helical path which encloses said bight, said 20 hook being arranged to engage the yarn B when the finger reaches its advanced position and to draw the yarn B around said bight and into a space between said bight and the yarn B in the retracting movement of said finger, and means 25 for tightening the knot and stripping it off said post.

17. In a weaver's knotter, devices for supporting a yarn A and a yarn B, the former being in the form of a bight enclosing the latter, said 30 devices including a member which holds the closed end of the bight, a hook, means for advancing and retracting said hook in a helical path which encloses said bight, said hook being arranged to engage the yarn B upon reaching its 35 advanced position and to draw the yarn B around said bight and into a space between said bight and the yarn B in the retracting movement of said hook, and means for tightening the knot and stripping it off said member.

18. In a weaver's knotter, means to support a yarn A and a yarn B, the former being in the form of a bight enclosing the latter, a hook, and means for advancing and retracting said hook in a helical path which encloses said bight, said hook being arranged to engage the yarn B upon reaching its advanced position and to draw the yarn B around 45 said bight and into a space between said bight and the yarn B in the retracting movement of said hook.

19. In a weaver's knotter, means to support a yarn A and a yarn B, the former being in the form of a bight enclosing the latter; a helical finger having a hook at its tip; and means for advancing and retracting said finger in a helical path which encloses said bight, the axis of said 50 finger extending in the direction of said bight, said hook being arranged to engage the yarn B when the finger reaches its advanced position and to draw the yarn B around said bight and into a space between said bight and the yarn B in the retracting movement of said finger.

20. A weaver's knotter comprising two substantially parallel spaced plates having slots for supporting yarns A and B, the lower ends of the slots for the yarn A terminating at different heights so as to support the yarn A in inclined position and the lower ends of the slots for the yarn B terminating at different heights so as to support the yarn B in a position inclined opposite to the 65 yarn A; knot-forming means between said plates, said knot-forming means including a stationary pin located adjacent to the crossing point of the yarns, means to bend the yarn A and a portion of the yarn B over said pin, and means to cut 70 75

off the waste ends of the yarns, said bending means placing said yarns within reach of said cutting-off means; and means for stripping the knot from said knot-forming means and tightening the knot.

21. A weaver's knotter comprising two substantially parallel spaced plates having slots for supporting yarns A and B, the lower ends of the slots for the yarn A terminating at different heights so as to support the yarn A in inclined position and the lower ends of the slots for the yarn B terminating at different heights so as to support the yarn B in a position inclined opposite to the yarn A; means associated with certain of said slots for causing frictional resistance to movement in said slots; knot-forming means between said plates, said knot-forming means including a single shear to sever the ends that extend through the slots in one of said plates and means to bring both yarns within reach of said shear; and means for stripping the knot from said knot-forming means and tightening the knot.

22. A weaver's knotter comprising two substantially parallel spaced plates having slots for supporting yarns A and B, the lower ends of the slots for the yarn A terminating at different heights so as to support the yarn A in inclined position and the lower ends of the slots for the yarn B terminating at different heights so as to support the yarn B in a position inclined opposite to the yarn A; means associated with said slots for causing frictional resistance to movement of said yarns in said slots; knot-forming means between said plates, said knot-forming means including a single shear to sever the ends that extend through the slots in one of said plates; and means engaging one of said yarns at a point between the other plate and said knot-forming means for stripping the knot from said knot-forming means and tightening the knot.

23. In a knotter, devices to support two yarns, with one of the yarns in the form of a bight enclosing the other yarn, a helical finger having a hook at its tip, and means for advancing and retracting said finger in a helical path that encloses said bight, to draw the last-mentioned yarn around said bight.

24. In a knotter, means to support two yarns, means for drawing one of the yarns into the form of a bight enclosing the other yarn, means for severing the last mentioned yarn, and a reciprocating helical finger having a hook at its tip for drawing the shortened end of the last-mentioned yarn around said bight.

25. A knotter comprising means to support two yarns; means for drawing one of the yarns into the form of a bight enclosing the other yarn; a helical finger having a hook at its tip; a tubular screw to which said finger is attached; a shaft extending into said screw and having a splined connection therewith; a gear train for rotating said screw in opposite directions; a pivoted member having a cam for actuating said gear train; a spring tending to move said pivoted member in one direction; a lever having a pawl arranged to engage said pivoted member and cause the latter to move with the lever against the influence of said spring; and means for disengaging the pawl from said member.

26. In a knotter, means to support two yarns; means for drawing one of the yarns into the

form of a bight enclosing the other yarn; a helical finger having a hook at its tip; a tubular screw to which said finger is attached; a shaft extending into said screw and having a splined connection therewith; a gear train for rotating said screw in opposite directions, a pivoted member for actuating said gear train, a spring tending to move said pivoted member in one direction, and means for moving said member in the opposite direction.

27. A knotter comprising yarn-manipulating means, a pivoted member for actuating said means, a spring tending to move said pivoted member in one direction, a lever having a pawl arranged to engage said pivoted member and cause the latter to move with the lever against the influence of said spring, and means for disengaging the pawl from said member.

28. In a knotter, a rotary knot-forming element, a gear train for rotating said element in opposite directions, said gear train comprising a pinion, a segment gear meshing with said pinion, a segment pinion rigid with the segment gear, and a second segment gear meshing with said segment pinion, means to limit oscillatory movement of one of said gear elements, and means for oscillating the second-mentioned gear segment, said means including lever-operated means for moving said gear segment in one direction, and a spring for moving said gear segment in the opposite direction.

29. A knotter comprising means to support two yarns; mechanism to form said yarns into a knot; means to cut off the waste portions of the yarn; means to tighten the knot; a pivoted member for actuating said mechanism, said cutting-off means and said tightening means; a spring for moving said member in one direction; a lever for moving said member in the opposite direction, and means for disengaging said member from said lever to permit the return of the member by the spring.

30. A knotter comprising means to support two yarns; mechanism to form said yarns into a knot; means to cut off the waste portions of the yarn; means to tighten the knot; a pivoted member for actuating said mechanism, said cutting-off means and said tightening means; a spring for moving said member in one direction; a lever; a pawl on the lever to engage said member when said lever is swung in the opposite direction, and means for disengaging said pawl from said member to permit the return of the latter by the spring.

31. A hand knotter comprising knot-forming means; a pivoted member for actuating said means; a spring for moving said member in one direction; a digitally-actuated lever for moving said member in the opposite direction; and means for disengaging said member from said lever to permit the return of the member by the spring.

32. Yarn-supporting devices for a weaver's knotter comprising means to support each of two yarns A and B at two separated points; a post located about midway between said points; a second post near the first post; and means for holding the yarn A in the form of a bight enclosing the yarn B, and for holding the yarn B bent around the second post with a portion of the yarn B adjacent to the end portions of said bight.

EDWARD HALL PARKER.
